UNITED STATES PATENT OFFICE.

ARTHUR DON PUERNER, OF BUTTE, MONTANA, ASSIGNOR OF ONE-THIRD
TO T. G. HEINE, OF BUTTE, MONTANA.

SHOE.

SPECIFICATION forming part of Letters Patent No. 725,771, dated April 21, 1903.

Application filed December 11, 1902. Serial No. 134,832. (No model.)

To all whom it may concern:

Be it known that I, ARTHUR DON PUERNER, a citizen of the United States, residing at Butte, in the county of Silverbow and State of Montana, have invented certain new and useful Improvements in Shoes; and I do declare the following to be a full, clear, and exact description of the invention, such as will enable others skilled in the art to which it appertains to make and use the same.

This invention relates to shoes, and particularly to waterproof shoes designed for the use of those working in copper-water, mines of various kinds, quarries, brick-yards, and elsewhere where a strong and durable waterproof shoe for the use of workmen is required.

The object of the invention is to provide a leather shoe, which is waterproof and adapted to last a considerable period under the roughest usage.

With these and other objects in view the invention consists of certain novel features of construction, combination, and arrangement of parts, as will be more fully described, and particularly pointed out in the appended claim.

In the accompanying drawings, Figure 1 is a perspective view of a shoe embodying my invention. Fig. 2 is a cross-section of the same. Fig. 3 is a horizontal section through the rear portion of the vamp and counter. Figs. 4, 5, and 6 are views similar to Fig. 1, showing different constructions of the outer vamp. Figs. 7, 8, 9, 10, and 11 are views of parts of the outer vamp and the body of the shoe.

The shoe may be made in any shape and style and of any preferred kinds of leather or other suitable material and is provided with an upper composed of a single piece of material properly shaped to form the quarters 1 and vamp 2, which are sewed or otherwise united at their rear edges. The lower edge of the vamp is inturned and sewed or nailed to the inner and outer soles 3 and 4 in any ordinary way. An outer protecting and reinforcing vamp 3', composed in the form shown in Figs. 1, 2, 3, and 7 of a single piece of leather, covers the entire outer surface of the vamp 2 and is sewed at its upper edge thereto by a line of stitching 4'. The lower

edge of this vamp 3' is also inturned and secured between the two soles and covers the crevice between the outer sole and vamp 2, thus preventing access of moisture at this point.

A back strap 5 is formed centrally with a finger-loop 6 for the usual purpose and has its ends arranged upon the inner and outer sides of the quarters at their point of union 60 and stitched thereto on opposite sides of the line of stitching uniting the quarters. The ends 3^a and 3^b of the vamp overlap upon the outer side of the outer portion of this strap and may be first united by cement and then secured to the outer ply or portion of the strap, the quarters, and inner vamp 2 by a line of stitches 7, extending up parallel with the edge of the outer end of the vamp 3' on one side of the center of the point of union 70 of the quarters, then across parallel with the upper edges of the vamp 3', and then down parallel with and on a line just inside the edge of the inner or underlying end of the vamp 3' on the opposite side of the point of union of the 75 quarters, thus forming a waterproof joint of maximum strength at the rear of the double vamp of the upper. In order to render the connection doubly secure, a rivet 8 may be employed between the two vertical parallel 80 portions of the stitching 7 to reinforce the same, thus providing a construction which is adapted to sustain the hardest kind of rough usage.

It will be seen by my construction of upper and outer vamp and mode of application of the latter a shoe of great strength and wearing qualities is produced, and that as the outer vamp prevents moisture from entering the shoe between the sole and upper and 90 from soaking through the inner vamp the shoe is rendered practically waterproof under all conditions of service. Hence our shoe is well adapted for the use of miners and others requiring a shoe embodying these 95 qualifications.

As shown in Fig. 4, the shoe may be made with an outside counter 3^c and outer half-vamp 3^d, formed of a toe-cap and side pieces 3^e, all in one piece, or with the same parts and separate toe-cap 3^f, as shown in Fig. 5, or with a half-vamp (toe-cap and side pieces in

one piece) alone, as shown in Fig. 6, and the construction may be modified in other respects, as desired.

5 Figs. 7, 8, 9, 10, and 11 show the blanks from which the several parts are formed.

From the foregoing description, taken in connection with the accompanying drawings, it is thought that the construction, operation, and advantages of my improved shoe will be 10 readily apparent without requiring a more extended explanation.

Various changes in the form, proportion, and the minor details of construction may be resorted to without departing from the principle or sacrificing any of the advantages of 15 this invention.

Having thus described my invention, what I claim as new, and desire to secure by Letters Patent, is—

20 A waterproof boot or shoe comprising inner and outer soles, an upper having a continuous vamp divided at the heel and having its divided edges overlapping, an outer vamp

sewed at its upper edge to the inner vamp and having its lower edge secured with the 25 lower edge of the inner vamp to and between the soles, said outer vamp being also divided at the heel and having its divided edges overlapping, a back strap having its ends lying, respectively, on the inner side of the inner 30 vamp and between the overlapping ends of the two vamps, a rivet passing through and uniting the outer end of the back strap and the divided ends of the vamps at a point between their edges, and lines of vertical stitching on opposite sides of the rivet and securing the edges of the divided ends of the vamps and the ends of the back strap together, substantially as described.

In testimony whereof I have hereunto set 35 my hand in presence of two subscribing witnesses.

ARTHUR DON PUERNER.
